UNITED STATES PATENT OFFICE.

BRYANT BANNISTER, OF PITTSBURGH, PENNSYLVANIA.

COMBINATION GAS AND COAL FIRED FURNACE.

Application filed September 8, 1920. Serial No. 408,905.

To all whom it may concern:

Be it known that I, BRYANT BANNISTER, a citizen of the United States, and resident of Pittsburgh, in the county of Allegheny and State of Pennsylvania, have invented certain new and useful Improvements in Combination Gas and Coal Fired Furnaces, of which the following is a specification.

This invention relates to boiler furnaces, and more particularly to combined gas and coal fired boiler furnaces, and has for one of its objects the provision of such a furnace that may be fired with either gas or coal alone, or combined gas and coal.

Another and important object is to provide a furnace of this class having walls of improved and novel design that will allow for expansion and contraction without bulging or breaking.

Still another object is to provide a furnace of this class having the gas burner and primary combustion chamber below the coal combustion chamber and floor level.

Heretofore furnaces of this class have been constructed for using gas and coal as fuel, but have proved unsatisfactory due to the incomplete combustion of the gases before they entered the boiler tubes, and also due to the fact that the furnace walls had a tendency to bulge inwardly and break due to the high temperature to which the inside furnace wall is subjected. The outside of the same wall remaining comparatively cool, expansion takes place, tending to elongate the inner surface.

The present invention will eliminate the faults of the furnaces of this class heretofore constructed. The gas burner and primary combustion chamber being completely below the coal combustion chamber and floor level, permits the isolation of burners, clean-out doors, etc. from the operating floor, and provides a long gas passage surrounded by refractory material for the completion of combustion after the gases leave the combustion chamber proper and before they enter the boiler tubes.

The walls of my improved furnace are inclined outwardly and, therefore, will not have a tendency to bulge inwardly and break as do the walls of the furnaces heretofore constructed.

These and other objects and advantages

will be more fully brought out in the following specification, and illustrated in the accompanying drawings, in which—

Figure 1 is a partial longitudinal sectional elevation through a boiler furnace embodying my invention.

Figure 2 is a sectional plan taken on the line II—II of Figure 1.

Referring more particularly to the drawings, in which a single boiler furnace is illustrated, the numeral 2 designates the pit in which the furnace is built, and 3 designates the floor of the building or boiler room which is supported on I-beams 4 extending from the side walls 5 of the room to the furnace upright supports 6.

The side walls 7 and 8 of the furnace which are composed of fire-brick or other refractory material, are inclined outwardly on an angle and are supported by a plurality of steel girder supports 9, so that the weight of the walls will always be so centered that the tendency remains for the walls to rest upon the supporting steel work rather than to fall or bulge inwardly toward the furnace.

The gas combustion chamber 10 is built below the floor level and comprises a bottom 11 of refractory material having a dust collector 11^a and supported on transverse girders 12 secured to the upright 6 and dividing and supporting wall 13. The chamber 10 has outwardly inclined side walls 14 and 15 of refractory material supported similar to the walls 7 and 8 by steel girder supports 16. A suitable top 17 is formed over the admission end of the chamber 10 and may be of arched formation or any suitable construction as desired.

The side wall 8 of the main furnace construction extends downwardly an appreciable distance below the top 17 of the gas combustion chamber forming a hanging ignition wall 18.

The side or front wall 14 extends upwardly an appreciable distance above the floor level forming the back wall 19 of a coal combustion chamber 20, which extends from the back wall 19 to the wall 7.

The coal combustion chamber is adapted to be fired by a stoker mechanism 21 adapted to receive coal through the entrance port 22 and to discharge ashes into a bunker 23.

which in turn dumps them into a car 24 running on track 24* in the pit 2 for removal.

A gas main 25 is shown on the outside of 5 the rear wall 5, although it will be understood that the location of this main may be within the building if desired. The main 25 is provided with a stand pipe 26 having a T-connection 27 adjacent its top, and an outlet or clean-out door 28 at its bottom.

A gas feed pipe 29 extends from the T-connection 27 to a burner 30 having a mushroom valve 31 for controlling the inlet of gas. A fan 32 supplies air under pressure 15 to the air box 33 from which it is conveyed through pipe 34, having a butterfly control valve 35 therein, to the burner 30. The gas burner and its directly associated mechanism not being a part of this 20 invention, will not be described further in detail.

Preferably blast furnace gas will be burned in this furnace, although any other form of gas may be used. It is well known 25 that blast furnace gas carries a large quantity of dust and small particles of foreign matter with it, and these particles have a tendency to settle and in time would clog and fill up the burners, pipes, and 30 chambers. However the stand pipe 26, dust collector 11*, and suitable clean-out door or opening 37 are provided to allow for the removal of such foreign matter. Other clean-out doors or openings 38 and 39 are 35 formed in the upper portion of the gas combustion chamber and lower portion of the coal combustion chamber, respectively, for permitting access to these parts for cleaning and repairs.

40 While I have shown and described this invention as applied to a single boiler, it will be understood that it is adapted to be applied to a battery of boilers, or single boiler, as desired, or to other uses than 45 boiler-heating.

The operation of the furnace is as follows—

Coal or other solid fuel is fed into the coal combustion chamber 20 through the 50 stoker 21, and the products of combustion are adapted to pass upwardly over the wall 19 and into or around the boiler tubes. The gas flows from the main 25 down through the stand pipe 26, T-connection 27, feed pipe 55 29, to the burner 30, where it is mixed with air under pressure from fan 32 and flows into the combustion chamber 10 where combustion is completed and the products of combustion pass upwardly between the walls 19 and 8 into or around the boiler tubes.

60 It will readily be apparent that either coal alone, gas alone, or combined gas and coal may be used to fire this furnace. The combustion chambers are entirely separated.

65 Therefore, there will be no loss of heat when

only one chamber is in operation. However, the novel arrangement and combination of chambers provides for the products of combustion remaining apart until combustion is complete, and then combining 70 them for passage into or around the boiler tubes.

While I have illustrated and described one particular form of my invention, various modifications may be made within the scope 75 of the appended claims by those skilled in the art, without departing from the spirit of my invention.

I claim:—

1. A combined coal and gas fired boiler 80 furnace comprising in combination, a coal combustion chamber above the floor level, a back wall along the rear end of said chamber and extending upwardly an appreciable distance so as to direct the products 85 of combustion from said chamber against the boiler being heated, a gas combustion chamber located materially below the floor level at a point to the rear of said back wall, said chamber having an ignition wall 90 therein for retarding the passage of gas therethrough until combustion is established, the portion of said gas combustion chamber beyond said ignition wall being of constantly increasing cross sectional area towards the 95 boiler to provide for the expansion of the gas as combustion takes place, and means for supplying air and gas to said gas combustion chamber.

2. In a combined coal and gas fired boiler 100 furnace, a coal combustion chamber above the floor level, a back wall along the rear end of said chamber and extending upwardly an appreciable distance so as to direct the products of combustion from said 105 chamber against the boiler being heated, a gas combustion chamber extending substantially vertically from a point materially below the floor level to the upper end of said back wall, thereby providing a long passage 110 for the products of combustion, the side walls of said chambers being composed of refractory material and inclined outwardly, thus providing a constantly increasing cross 115 sectional area towards the boiler to provide for the expansion of the products of combustion, and also providing for the weight of the walls to be so centered that they will not bulge inwardly.

3. In a combined coal and gas fired boiler 120 furnace, a coal combustion chamber above the floor level, a back wall along the rear end of said chamber and extending upwardly an appreciable distance so as to direct the products of combustion from said 125 chamber against the boiler being heated, a gas combustion chamber extending substantially vertically from a point materially below the floor level to the upper end of said back wall, thereby providing a long pas- 130

- sage for the products of combustion, the side walls of said chambers being composed of refractory material and inclined outwardly, thus providing a constantly increasing cross sectional area towards the boiler to provide for the expansion of the products of combustion, and also providing for the weight of the walls to be so centered that they will not bulge inwardly, means for supplying a mixture of air and gas to said gas combustion chamber, and suitable clean-out doors and apertures in both of said chambers.
4. A combined coal and gas fired boiler furnace comprising in combination, a coal combustion chamber above the floor level, an automatic stoker for feeding coal into said chamber, and a back wall along the rear end of said chamber and extending upwardly an appreciable distance above said stoker, and adapted to direct the products of combustion from said coal against the boiler being heated, a gas combustion chamber below the floor level at a point to the rear of said back wall, said chamber having an ignition wall therein for retarding the passage of gas therethrough until combustion is established, the portion of said gas combustion chamber beyond said ignition wall being of constantly increasing cross sectional area toward the boiler to provide for the expansion of the gas as combustion takes place, and means for supplying a mixture of air and gas under pressure to said gas combustion chamber, said combustion chambers being adapted to be operated separately or in unison.
5. A combined coal and gas fired boiler furnace comprising in combination, a coal combustion chamber above the floor level, an automatic stoker for feeding coal into said chamber, and a back wall along the rear end of said chamber and extending upwardly an appreciable distance above said stoker, and adapted to direct the products of combustion from said coal against the boiler being heated, a gas combustion chamber below the floor level at a point to the rear of said back wall, said chamber having an ignition wall therein for retarding the passage of gas therethrough until combustion is established, the portion of said gas combustion chamber beyond said ignition wall being of constantly increasing cross sectional area toward the boiler to provide for the expansion of the gas as combustion takes place, and means for supplying a mixture of air and gas under pressure to said gas combustion chamber, said combustion chambers being adapted to be operated separately or in unison.

In witness whereof I have hereunto signed my name.

BRYANT BANNISTER.
